UNITED STATES PATENT OFFICE.

WILLIAM N. BEST, OF BROOKLYN, NEW YORK.

DESIGN FOR A BUTTON, BADGE, WATCH-CHARM, OR LOCKET.

54,978.

Specification for Design.

Patented Apr. 27, 1920.

Application filed January 7, 1918. Serial No. 210,774. Term of patent 7 years.

To all whom it may concern:

Be it known that I, WILLIAM N. BEST, a citizen of the United States, and a resident of New York, borough of Brooklyn, in the county of Kings and State of New York, have invented a new, original, and ornamental Design for Buttons, Badges, Watch-Charms, or Lockets, of which the following is a specification, reference being had to the accompanying drawing, forming a part thereof, which represents a face view of a button, badge, watch-charm, or locket embodying my invention.

The design consists of a circular field, a

cross disposed on the major axis thereof, stars at either side of the base of the cross, the word "I" at the left of the cross, the word "give" at the right of the cross and the words "for the cause of God and righteousness" at the edge of the field, the lettering and stars being in blue and the cross in red on a white background.

I claim:

The ornamental design for a button, badge, watch-charm, or locket, as shown and described.

WILLIAM N. BEST.
